UNITED STATES PATENT OFFICE

2,155,638

CARBURETOR

Robert F. Bracke, Chicago, Ill.

Application February 6, 1935, Serial No. 5,203

1 Claim. (Cl. 261—72)

This invention relates to carburetors and particularly to carburetors of the fuel lift type in which the suction of the engine applied to the carburetor is adapted through suitable depression amplifying means to raise the necessary supply of fuel from the fuel tank.

One of the objects of the invention is to provide an improved fuel lift carburetor.

A further object of the invention is to provide a fuel lift carburetor of simplified construction.

A further object of the invention is to provide a fuel lift carburetor adapted to exert a substantially uniform fuel lift suction, irrespective of engine speed and without means connected to the engine controls.

Other objects and advantages will become apparent as the description proceeds.

In the drawing, the figure is a vertical section through a preferred embodiment of my invention and diagrammatically shows this embodiment connected to the main fuel tank.

Referring to the drawing, the carburetor is designated by the reference numeral 10 and the fuel tank, which is normally located at the rear end of the vehicle and at a lower level than the carburetor, is designated by the reference numeral 11.

The carburetor comprises a main body portion 12 which is provided with an annular seat 13 against which abuts the upper edge of a removable shell 14 forming a fuel chamber 14a. The shell 14 is provided with a central opening through which is adapted to pass a cylindrical stem 15 depending from the carburetor body 12. The shell 14 is connected to the stem 15 by means of a knurled nut 16. Suitable gaskets are employed at the seat 13 and the upper end of the nut 16 to render the shell 14 liquid-tight in assembled relation. The stem 15 is internally shouldered at 17 and 18. The portion of the stem above the shoulder 18 is internally threaded to receive a correspondingly threaded portion of a Venturi tube or nozzle 19. The Venturi tube 19 is conformed so as to establish an annular passage 20 located between the shoulders 17 and 18. This annular passage communicates through a duct 21 with a low point within the chamber 14a. The Venturi tube 19 is provided

50 with ducts 22 which lead from the annular passage 20 into the throat of the Venturi tube. The stem 15 terminates inside a secondary air chamber 23. The Venturi tube 19 extends through this chamber and terminates thereabove in the 55 throat of a Venturi tube 24 formed in the body

12 of the carburetor. The Venturi tube 24 is located at the bottom of a mixing chamber 25, the outlet from which is controlled by a throttle valve 26 which may be of the usual butterfly type.

Within the chamber 14a is provided a float 27 of known type which actuates a valve 28 to control the outlet of a pipe 29 and maintain a substantially constant level of liquid fuel within the shell 14. The pipe 29 leads back to the fuel tank 11 and extends thereinto.

One side of the secondary air chamber 23 is provided with an enlarged port 30 for the admission of secondary air. An automatic valve 31 is provided to control the admission of this air. The valve 31 is provided with a stem 32, which stem is supported in a boss 33 carried by a spider 34 mounted in the port 30. An abutment member 35 is mounted on the outer end of the stem 32 and a coil spring 36 is located around the stem 32 so as to bear against the boss 33 and against the abutment member 35 so as to tend to move the valve 31 outwardly to closed position.

In the wall of the chamber 23 opposite the port 30, and preferably substantially in the center of said port, a duct 37 is provided which communicates with a downwardly directed bore 38, the upper end of which is threaded to receive the correspondingly threaded end of a small Venturi tube 39. The lower end of the bore 38 is enlarged so as to provide, in cooperation with the Venturi tube 39, an annular chamber 40. The annular chamber 40 communicates through ducts 41 with the throat of the venturi 39 and by means of a duct 42 in the body 12 of the carburetor, with the upper portion of the chamber 14a. A screw 43 provided with a knurled nut 44 is provided for the purpose of constricting, to an adjustable extent, the outlet of the Venturi tube 39. A lock nut 45 is provided to maintain the screw 43 in the desired position of adjustment.

The operation of the carburetor is as follows. At low and idling speeds the suction of the engine draws primary air through the stem 15, and the Venturi tube 19 draws fuel through the conduit 21 from the chamber 14a. The suction of the engine is communicated through conduit 37 to Venturi tube 39 with the result that a greater suction is produced in the conduit 42 and, consequently, in the upper portion of the chamber 14a. As liquid fuel is taken from the chamber 14a, the float 27 falls and the valve 28 is opened so that this suction may elevate liquid through 55

pipe 29 from fuel tank 11. This operation maintains a substantially constant level of liquid in the chamber 14. The knurled nut 44 is adjusted so as to give the desired vacuum lift in the chamber 14a.

When the speed of the engine is increased by opening the throttle valve 26, the vacuum within the mixing chamber 25 and Venturi tube 24 creates a greater flow of primary air through the stem 15 and consequently a greater supply of liquid fuel through the duct 21. The vacuum in the secondary air chamber 23 is sufficient to open the valve 31 against the closing tendency of the spring 36. The degree of opening of the valve 31 depends upon the speed of the engine, being greater for high speeds and less for lower speeds. I have found that the air coming in past the lower edge of the valve 31 impinges against the opposite wall of the chamber 23 and creates a relatively high pressure in the bottom zone of the chamber 23. The vacuum in the upper portion of the chamber 23 is considerably greater. By entering the duct 37 into the secondary air chamber 23 at a point of intermediate height, I am enabled to subject the duct 37, and consequently the Venturi tube 40, to a vacuum or depression of intermediate degree, which is substantially constant for all speeds of the engine. The result is that the vacuum within the chamber 14a is substantially constant and supply of liquid fuel in large quantity to the venturi 19 at high speeds is not interfered with by an excessive vacuum in the chamber 14a.

It will be noted that the secondary air is admitted into the chamber 23 from one side and that the duct 37 opens into a side opposite there-

to, the secondary air passing to the engine through the top intermediate these two sides. That is, the incoming secondary air is subjected within the secondary air chamber to a change in direction which has the effect of establishing pressure differences therein. The fuel lift Venturi tube connects to the secondary air chamber at a point of intermediate pressure.

Although the invention has been described in connection with the specific details of a preferred embodiment thereof, it must be understood that such details are not intended to be limitative of the invention except in so far as set forth in the accompanying claim.

Having thus described my invention, what I claim as new and desire to secure by Letters Patent of the United States is:

A fuel lift carburetor comprising a body portion having formed therein at its upper end a mixing chamber, the lower end of said mixing chamber being of Venturi tube formation, a secondary air chamber in said body below said Venturi tube and open at one side for the admission of secondary air, a fuel chamber removably secured to the lower end of said body, a primary air inlet extending through said chamber and a main Venturi tube extending through the secondary air chamber into first said Venturi tube formation, and a fuel lift Venturi tube communicating with the secondary air chamber at a point opposite and substantially central with respect to the secondary air inlet, said point being free from local interruptions to the normal flow of air through said chambers.

ROBERT F. BRACKE.
